MEANS FOR DRAINING ACCUMULATED
MOISTURE FROM STORAGE TANKSRussell C. Churchman, Des Moines, Iowa; Nellie
Churchman executrix of said Russell C.
Churchman, deceased

Application March 1, 1946, Serial No. 651,261

11 Claims. (Cl. 230—1)

1

This invention relates to means in combination with a compressor unit and storage tank to drain any accumulated moisture from the storage tank and more particularly is an improvement over Patent 2,330,027 issued September 21, 1943, of which applicant is a co-inventor and pending application Serial No. 625,225, filed October 29, 1945, of which applicant is the sole inventor.

One problem in compressing air and storing the same is a change in the equilibrium conditions of the original atmosphere. The moisture content, present in the atmosphere as a vapor, drops out of the air as a liquid upon increased pressure and is present in the bottom of the storage tank. If the moisture is not drained from the storage tank, it continues to build up, cutting down the capacity of the storage tank for compressed air, and it passes out with the compressed air and creates trouble; for example it has a corrosive effect on any metal parts contacted and dilutes any material sprayed, such as paint. Petcocks on the bottom of storage tanks have been provided to manually drain any accumulated moisture from the storage tanks but they have proved ineffective in that operators neglect attending to this chore.

It is an object of the invention among others to provide means in combination with any type compressor unit and storage tank to automatically drain accumulated moisture from the storage tank.

It is another object of the invention to provide means in combination with an unloader tank of a compressor and storage tank to automatically drain accumulated moisture from the storage tank after the compressor stops.

It is still another object of the invention to provide means in combination with a compressor unit of the type not having an unloader tank; and a storage tank to automatically drain moisture from the storage tank at some period during the operation of the compressor unit.

It is a still further object of the invention to provide means in combination with a compressor unit of the type not having an unloader tank; and a storage tank to automatically drain moisture from the storage tank for a predetermined time interval at some period during the operation of the compressor unit.

It is a still further object of the invention to provide a means automatic in operation which is economical to manufacture, durable and efficient in use, easy to install and maintain and easy of adjustment. The means is further adaptable to be placed on new compressor units

2

or may be installed on compressor units already installed. Other objects will become apparent from a detailed description to follow in conjunction with the drawing.

- 5 In carrying out the objects of the invention there is provided a compressor unit connected to a storage tank with the compressor unit maintaining pressure in the storage tank at a predetermined pressure. A check valve is placed between the compressor unit and storage tank. Means are provided for draining accumulated moisture from the storage tank comprising a valve structure in the combination with the valve structure having a housing. An inlet connects with the bottom of the storage tank and housing with an outlet leaving the housing to a point of disposal and said outlet located above the inlet. The inlet and outlet are connected by a passage in the housing which may be a vertical passage 10 having a valve seat on top of the vertical passage. A valve member is seated on the valve seat with the valve member being attached to a piston movable within the housing above the valve seat. Spring means act against the piston to hold the 15 valve in seated position on the valve seat against pressure from the storage tank and a source of fluid pressure enters the housing below the piston at intervals to raise the piston and in turn, the valve off the valve seat to drain accumulated 20 moisture from the storage tank. The source of fluid pressure enters the housing into a chamber above the valve seat and sealed from the inlet, vertical passage and outlet with the said valve member attached to a rod extending through a 25 seal between the chamber and inlet, vertical passage and outlet and sealed therewith. The rod is attached to the piston which is movable within the chamber. There are also means connecting with the chamber in the form of a restricted outlet passage from the chamber to regulate the 30 time interval that the valve remains open.

40 As one species of the invention, there is provided a compressor unit having an unloader tank and connected to a storage tank with said compressor unit maintaining pressure in the storage tank at predetermined pressure. An electric switch is included for starting and stopping the compressor unit while a check valve is mounted between the compressor unit and storage tank. There are means for draining accumulated moisture from the storage tank comprising the same valve structure as described previously. There is a relief valve connected with the electric switch which controls a conduit leading from the unloader tank to the valve structure with said relief 45 50 55

valve being closed when the electric switch is closed and open when the electric switch is open. The source of fluid pressure to operate the valve structure comes from the unloader tank when the compressor stops, in this species.

In a second species there is provided a compressor unit connected to a storage tank with said compressor unit maintaining pressure in the storage tank at a predetermined pressure. An electric switch is included for starting and stopping the compressor unit. There are means for draining accumulated moisture from the storage tank which comprises the valve structure previously described connected to the bottom of the storage tank. A conduit is connected into the storage tank to deliver a pressure fluid from the storage tank to the valve structure. An electrically actuated valve is mounted in the conduit to control flow of pressure fluid in the conduit. The valve in the conduit is controlled by an electrical actuation means which electrical actuation means is connected electrically with the electric switch. The electrical actuation means is only operable to actuate the valve in the conduit when the electric switch is closed with said electrical actuation means operating soon after the compressor starts into operation for a predetermined time interval and said valve in the conduit being opened only once each time the compressor unit operates. The said conduit delivers the pressure fluid to the valve structure to open the valve structure and allow accumulated moisture from the storage tank to drain through the valve structure when the electrically actuated valve in the conduit is opened. The electrical actuation means is automatically reset to operate again each time the compressor unit stops.

With the foregoing and other objects in view, the invention will be more fully described herein-after and will be particularly pointed out in the claims appended hereto.

In the drawings, wherein like symbols refer to like or corresponding parts throughout the several views:

Figure 1 is a diagrammatic view showing the combination of a compressor unit, storage tank, and valve structure with the compressor unit including an unloader tank.

Figure 2 is a diagrammatic view showing the combination of another type compressor unit, a storage tank, valve structure and electrical actuation means to operate a valve in a conduit connecting the storage tank and valve structure.

Figure 3 is a sectional view of the valve structure with the valve member shown in elevation.

Figure 4 is a sectional view taken on line 4-4 of Figure 3 with part of the valve structure housing shown in elevation.

Figure 1 of the drawing indicates a crankshaft housing 1 connected with a compressor 6 through conduit 2 and check valve 3 with a storage tank 4. The compressor 6 is connected to an electric motor 5 and said compressor 6 operated in the usual manner by the motor 5. The compressor 6, crankshaft housing 1 and motor 5 along with a switch 7 make up a compressor unit. The compressor 6 has an unloader tank in the form of conduit 2 connected therewith which conduit 2 receives compressed air from the compressor 6 for passage to storage tank 4.

In the operation of the compressor unit, the storage tank 4 containing compressed air is connected with means for using the compressed air. The maximum pressure on the air in storage tank 4 is maintained at say 125 pounds per square

inch. When sufficient air has been used from storage tank 4 to reduce the pressure in the storage tank to say 90 pounds per square inch, electric switch 7, which is connected into storage tank 4 (not shown) and actuated by the pressure of fluid in storage tank 4, is closed. Switch 7 is connected to motor 5 (not shown) and when closed, allows electric current to flow to motor 5 and thus start motor 5 into operation. Motor 5 is not of a sufficient over-size to start into operation against 90 pounds per square inch pressure, hence the compressor 6 empties into conduit 2 which in the present embodiment is an unloader tank. The pressure in the unloader tank or conduit 2 builds up gradually, until it exceeds the pressure in storage tank 4 when check valve 3 opens and allows the air under pressure from conduit 2 to flow into storage tank 4. The compressor unit will operate until the pressure in the storage tank 4 reaches the maximum pressure for which the switch 7 is set. When this point is reached, the pressure fluid in storage tank 4 will exert its pressure on electric switch 7 to open the switch and cut off supply of electric power to motor 5. The pressure fluid in storage tank 4 holds check valve 3 seated and the opening of switch 7 also opens a relief valve 8 which allows conduit 2 to be exhausted and pressure in conduit 2 established at atmospheric so it will not be necessary for the compressor unit to start up against a pressure head. The operation of the compressor unit with the unloader tank is the same as for units now on the market and being offered for sale commercially and applicant lays no claim to novelty for this feature. The relief valve 8, through which the fluid under pressure from conduit 2 flows connects into conduit 9 which conduit in turn connects into a valve structure 10.

The valve structure 10 has a housing member 11 which is made in two pieces as shown in order to allow ease of assembling the valve structure. The housing 11 has an inlet 12 connecting into the bottom of storage tank 4 through which any accumulated moisture in storage tank 4 can be drained. The housing 10 has an outlet 13 leading to a point of disposal for the accumulated moisture and a passage 14 in the housing, which may be a vertical passage, to connect the inlet 12 and outlet 13 to make a conduit through the housing. The passage 14 has a valve seat 15 on top of the passage 14 and within the housing and a valve stem 16 on seat 15 to close off passage 14. The valve stem 16 is connected to a piston 17 which is reciprocal within a chamber 18 in housing member 11 and a spring 19 acts against a piston 17 to force it downwardly and in turn, keep the valve stem 16 seated on valve seat 15. The conduit 9 connects into chamber 18 through an entrance 20 in housing 11 to deliver pressure fluid from conduit 2 when relief valve 8 is open. The pressure fluid enters under piston 17 tending to force piston 17 upwardly against spring 19 thus putting spring 19 under tension. An outlet 21 leads from chamber 18 to allow the fluid pressure to exhaust from chamber 18. The outlet 21 has a restricted passage 22 which may be controlled by adjustable screw 23 to vary the size of restricted opening 22. By varying the size of opening 22, the time interval that the valve stem 16 is lifted off valve seat 15 can be controlled by the time required to exhaust chamber 18 of pressure fluid. The chamber 18 is sealed from inlet 12, passage 14 and outlet 13 by means of gasket 24 and valve stem 16 also passes through gasket 24 and is sealed therewith. An opening 25 is pro-

vided in the top of housing 11 to allow any pressure fluid that leaks by piston 17 to pass out to the atmosphere.

It is noted that valve stem 16 seals against the inlet end 12 and passage 14 only, hence the valve stem 16 is sealing against pressure from the storage tank 4 at all times. The accumulated moisture from storage tank 4 carries with it dirt, grease and all kinds of matter in suspension hence it is extremely easy for any valve controlling the inlet end of a valve connecting with a storage tank to clog. The present valve stem structure receives the full force of pressure from the storage tank 4 which in turn has a cleansing action on the valve stem end, keeping it clean which allows it to seat on the valve seat 15 and close off flow at all times. The passage 14 is made about one-quarter inch in diameter while the spring is calibrated to exert a pressure of approximately twenty pounds per square inch, which allows approximately a 16 to 1 ratio in opening. The pressure of fluid in storage tank 4 never reaches a point where it can lift valve stem 16 off valve seat 15 against the force of spring 19 over the greater area of piston 17. Pressure fluid entering chamber 18 exerts a greater pressure than spring 19 over the same area hence piston 17 is raised.

In Figure 2 is disclosed a compressor unit, differing from the compressor unit of Figure 1 only in the instance that it has no unloader tank in conjunction with the compressor. As in Figure 1 the crankshaft housing is represented at 1 with a conduit 2 connecting a compressor 6 to storage tank 4 through a check valve 3. A motor 5 operates the compressor 6 and is of sufficient oversize to start compressor 6 into operation against pressure of fluid in storage tank 4. An electric switch 7 controls operation of the compressor unit just as previously described for Figure 1. A conduit 9, in the present instance, connects into storage tank 4 above the level of any accumulated moisture in storage tank 4 and delivers pressure fluid from storage tank 4 to valve structure 10, to actuate the valve structure 10 as previously described for Figure 1 where pressure fluid was taken from conduit 2. The valve structure 10, used in Figure 2 is the same structure as employed in Figure 1 with this one exception, the adjustment on exhaust outlet 21 is not essential as it can be left fully open.

Mounted in the conduit 9 is a valve 26 to control flow through the conduit 9 with the valve 26 being opened by an electrical actuation means, shown generally at 27. The valve 26 has a spring means within the valve (not shown) to keep the valve in closed position when the valve is not actuated by electrical actuation means 27.

The electrical actuation means connects into switch 7 by conductors running from the same lead posts that connect to conductors running to the motor 5. In the drawing at Figure 2, the switch is shown as open but when the switch is closed, electric current will run to both the motor 5 and electrical actuation means 27. Electric current flows first to a heating element, shown diagrammatically at 28, which is a button-type flasher or circuit breaker of either 60 or 100 watts. This is a commercial product on the market and applicant plans to purchase this item and include it in the combination. In operation, the heating element 28 acts more or less as a switch means and does not allow electric current to pass therethrough until it heats sufficiently to close contact's by expansion of the contacts on being heated. The contacts loose heat after

being contacted once hence tend to separate after a time interval which can easily be controlled by the size of resistors used. When electric current passes through the heating element 28, it flows to contact points 29 and 30 that are spaced and mounted on a bar 31. A pin member 32 allows electric current to flow between contact points 29 and 30, when pin member 32 contacts the points 29 and 30 as shown in Figure 2. Electric current will then flow to a solenoid 33, which will be energized and pull bar 31 downwardly and thus open valve 26 to allow pressure fluid to flow from storage tank 4, conduit 9, through valve 26 to valve structure 10.

It can thus be seen that the electrical actuation means 27 will operate soon after motor 5 starts into operation to allow pressure fluid from storage tank 4 to actuate valve structure 10. The time interval between the starting of motor 5 and the opening of valve 26 is dependent on the size of heating element 28 employed.

When bar 31 is pulled downwardly, pin member 32 will contact magnetic coil 34 which is electrically connected with switch 7, and will thus be magnetized the whole time switch 7 is closed and attract pin 32. When the contact points in heating element 28 are separated, electric current will no longer flow to solenoid 33 hence bar 31 is no longer held by the solenoid 33 and the spring 30 (not shown) in valve 26, will force valve 26 closed and at the same time force bar 31 upwardly. Bar 31 in moving upwardly will not carry pin 32 up with it since magnetic coil 34 is holding it. This will break electrical contact between contact points 29 and 30, hence electric current cannot again flow through heating element 28 to solenoid 33. When switch 7 is opened again as storage tank 4 reaches its maximum pressure, electric current to magnetic coil 34 is closed off, hence pin 32 is no longer held downwardly by the magnetic coil and a spring (not shown) mounted in bar 31 moves pin 32 upwardly again into contact with contact points 29 and 30. Thus the electrical actuation means is set to operate again when electric switch 7 is closed and it can be seen that electrical actuation means will only function once each time motor 5 operates.

While the invention has been described in connection with specific embodiments, it is to be understood that the words which have been used are words of description rather than of limitation, and that practice of the invention within the scope of the appended claims may be resorted to without departing from the true scope of the invention in all its aspects.

I claim:

1. In combination, a compressor unit including an electric motor connected through an unloader space to a compressed air storage tank, an electric switch connected to the compressor unit and actuated by the air pressure in the storage tank, said electric switch being closed when the air pressure in the storage tank reaches a predetermined low to set the compressor unit into operation and said electric switch opened when the air pressure in the storage tank reaches a predetermined high to stop operation of the compressor unit, said compressor discharging into the unloader space until the pressure existing in the storage tank is reached after which the unloader space opens to the storage tank, a valve in a conduit connected to the bottom of the storage tank to drain any accumulated moisture from the storage tank through the valve to a disposed point, said valve normally closing off flow through the

conduit, said valve connected to the unloader space when the storage tank reaches the predetermined high pressure and the compressor unit stops, said air under pressure in the unloader space flowing to the valve to exert its pressure to open the valve for a limited time interval each time the compressor unit operates and said air in the unloader space exhausting to the atmosphere through the valve.

2. In combination, a compressor unit including an electric motor connected through an unloader space to a compressed air storage tank, an electric switch connected to the compressor unit and actuated by the air pressure in the storage tank, said electric switch being closed when the air pressure in the storage tank reaches a predetermined low to set the compressor unit into operation and said electric switch opened when the air pressure in the storage tank reaches a predetermined high to stop operation of the compressor unit, said compressor discharging into the unloader space until the pressure existing in the storage tank is reached after which the unloader space opens to the storage tank, a valve in a conduit connected to the bottom of the storage tank to drain any accumulated moisture from the storage tank through the valve to a disposed point, said valve normally closing off the flow through the conduit, said valve connected to the unloader space when the storage tank reaches the predetermined high pressure and the compressor unit stops, said air under pressure in the unloader space flowing to the valve to exert its pressure to open the valve for a limited time interval each time the compressor unit operates, said air under pressure in the unloader space exhausting through a passage in the valve to the atmosphere and adjustable means in the passage to restrict the passage.

3. In combination, a compressor unit including an electric motor connected to a compressed air storage tank, an electric switch connected to the compressor unit and actuated by the air pressure in the storage tank, said electric switch being closed when the air pressure in the storage tank reaches a predetermined low to set the compressor unit into operation and said electric switch opened when the air pressure in the storage tank reaches a predetermined high to stop operation of the compressor unit, said compressor unit discharging into the storage tank until the predetermined high pressure is reached, a first valve in a conduit connected to the bottom of the storage tank to drain any accumulated moisture from the storage tank through the first valve to a disposal point, said first valve normally closing off flow through the conduit, a second conduit connecting the air under pressure from the storage tank to the first valve to exert its pressure to open the first valve, a second valve in said second conduit controlling flow through the second conduit, an arm actuated by electrical means connected to the switch and said arm pulled downwardly when the switch is closed to open the second valve for a limited time interval each time the compressor unit operates to allow air under pressure to flow from the storage tank to the first valve with said air exhausting from the first valve to the atmosphere.

4. In combination, a compressor unit including an electric motor connected to a compressed air storage tank, an electric switch connected to the compressor unit and actuated by the air pressure in the storage tank, said electric switch being closed when the air pressure in the storage

tank reaches a predetermined low to set the compressor unit into operation and said electric switch opened when the air pressure in the storage tank reaches a predetermined high to stop operation of the compressor unit, said compressor unit discharging into the storage tank until the predetermined high pressure is reached, a first valve in a conduit connected to the bottom of the storage tank to drain any accumulated moisture from the storage tank through the first valve to a disposal point, said first valve normally closing off flow through the conduit, a second conduit connecting the air under pressure from the storage tank to the first valve to exert its pressure to open the first valve, a second valve in said second conduit controlling flow through the second conduit, an arm contacting the second valve to open the same, an electrical means connected to the switch through a heat control switch element, said electrical means operable to pull the arm downwardly when the heat control switch element is closed and the electric circuit to the electrical means broken when the arm moves upwardly so that the second valve is actuated once only each time the switch is closed.

5. In combination, a compressor unit including an electric motor connected to a compressed air storage tank, an electric switch connected to the compressor unit and actuated by the air pressure in the storage tank, said electric switch being closed when the air pressure in the storage tank reaches a predetermined low to set the compressor unit into operation and said electric switch opened when the air pressure in the storage tank reaches a predetermined high to stop operation of the compressor unit, said compressor unit discharging into the storage tank until the predetermined high pressure is reached, a first valve in a conduit connected to the bottom of the storage tank to drain any accumulated moisture from the storage tank through the first valve to a disposal point, said first valve normally closing off flow through the conduit, a second conduit connecting the air under pressure from the storage tank to the first valve to exert its pressure to open the first valve, a second valve in said second conduit controlling flow through the second conduit, an arm contacting the second valve to open the same, a solenoid electrically connected to the switch through a heat control switch element, said solenoid when energized operable to pull the arm downwardly to open the second valve when the heat control switch element is closed, an electro-magnet connected by a second circuit with the switch and energized when the switch is closed and a pin in the arm completing the circuit to the solenoid which pin contacts the electro-magnet and is held by the electromagnet to break the circuit to the solenoid when the arm moves upwardly after the heat control switch element opens.

6. In a compressor unit and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion leading to a point of disposal, a passage in the valve housing connecting the inlet with the outlet, a valve seat associated with the passage in the housing with a valve member seating on the valve seat to close off

the passage, a portion of said valve member extending into a chamber within the valve housing with means in the chamber to keep the valve member seated, an inlet for a source of fluid under pressure into the chamber to exert its pressure against the valve member to unseat the valve member and open the passage, an outlet passage from the chamber for the fluid under pressure and adjustable means in the outlet passage to restrict the size of the outlet passage.

7. In a compressor unit and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion above the inlet portion leading to a point of disposal, a passage in the valve housing connecting the inlet with the outlet, a valve seat associated with the passage in the housing with a valve member seating on the valve seat to close off the passage, a portion of said valve member extending into a chamber within the valve housing with a spring in the chamber to keep the valve member seated, an inlet for a source of fluid under pressure into the chamber to exert its pressure against the valve member to unseat the valve member and open the passage, an outlet passage from the chamber to exhaust the fluid under pressure to the atmosphere and adjustable means in the outlet passage to restrict the size of the outlet passage.

8. In a compressor unit and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion above the inlet portion leading to a point of disposal a passage in the valve housing connecting the inlet with the outlet, a valve seat associated with the passage in the housing, a valve member seating on the valve seat to close off the passage, said valve member attached to a piston movable within a chamber in the housing, spring means acting against the piston to hold the valve member in seated position on the valve seat against pressure from the storage tank, an inlet for a source of fluid under pressure into the chamber to exert its pressure against the piston to unseat the valve member and open the passage and an outlet from the chamber to exhaust the fluid under pressure to the atmosphere.

9. In a compressor unit including an electric motor and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion above the inlet portion leading to a point of disposal, a passage in the housing connecting the inlet with the outlet, a valve seat at one end of the passage, a valve member seated on the seat to close the passage, said valve member attached to a piston movable

within a chamber in the housing, spring means with the chamber acting against the piston to hold the valve member in seated position on the valve seat against pressure from the storage tank, an inlet for a source of fluid under pressure into the chamber to exert its pressure against the piston to unseat the valve member and open the passage, an outlet passage from the chamber to exhaust fluid under pressure to the atmosphere and adjustable means in the outlet passage to restrict the size of the outlet passage.

10. In a compressor unit including an electric motor and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion above the inlet portion leading to a point of disposal, a passage in the housing connecting the inlet with the outlet, a valve seat at one end of the passage, a valve member seated on the seat to close the passage, said valve member attached to a rod extending through a seal into a chamber, said rod attached to a piston movable within the chamber, spring means within the chamber acting against the piston to hold the valve member in seated position on the valve seat against pressure from the storage tank, an inlet for a source of fluid under pressure into the chamber to exert its pressure against the valve member through the piston to unseat the valve member and open the passage and an outlet from the chamber to exhaust fluid under pressure to the atmosphere.

11. In a compressor unit including an electric motor and storage tank to compress and store air under pressure wherein the compressor unit maintains pressure in the storage tank at a predetermined high pressure the improvement comprising a valve to connect into a storage tank to drain accumulated moisture from the storage tank intermittently with the valve having a housing, an inlet portion to be connected into the bottom of a storage tank, an outlet portion above the inlet portion leading to a point of disposal, a passage in the housing connecting the inlet with the outlet, a valve seat at one end of the passage, a valve member seated on the seat to close the passage, said valve member attached to a rod extending through a seal into a chamber, said rod attached to a piston movable within the chamber, spring means within the chamber acting against the piston to hold the valve member in seated position on the valve seat against pressure from the storage tank, an inlet for a source of fluid under pressure into the chamber to exert its pressure against the valve member through the piston to unseat the valve member and open the passage and a controlled outlet from the chamber to regulate the time of discharge of fluid under pressure from the chamber to thus control the time interval the valve member is unseated.
